UNITED STATES PATENT OFFICE.

WILLIAM H. THOMPSON, OF INDIANAPOLIS, INDIANA, ASSIGNOR OF ONE-HALF TO IRVING S. GORDON AND WILLIAM E. KURTZ, OF SAME PLACE.

NUT-LOCK.

SPECIFICATION forming part of Letters Patent No. 351,223, dated October 19, 1886.

Application filed June 1, 1886. Serial No. 203,728. (No model.)

To all whom it may concern:

Be it known that I, WILLIAM H. THOMPSON, a citizen of the United States, residing at Indianapolis, in the county of Marion and State of Indiana, have invented a new and useful Improvement in Nut-Locks, of which the following is a specification.

My invention relates to an improved nut-lock of that class in which the nut is secured against turning off by a key, which is driven between the nut and its washer after the nut has been screwed onto the bolt.

The accompanying drawings illustrate my invention.

Figure 1 is a side elevation. Fig. 2 is a section at *a*, Fig. 1. Figs. 3 and 4 represent elevations of opposite sides of the key.

My nut-lock is shown in the drawings as applied to the ordinary joint-bolts of a rail-joint.

A is the rail, *B* the fish-bar, and *c c* are the bolts.

D D are a pair of rectangular washers, connected by a bar, *e*, and adapted to be slipped upon the bolts *c c* and to rest against the fish-bar. Said washers are each provided on their outer face with a groove, *f*, the portion *h* remaining above the groove being thinner than the rest of the washer.

E is the key for securing the nut on the bolt. Said key consists of a central web, *i*, having on one side a rib, *j*, adapted to fit loosely in the groove *f* on the washer, and a flange, *k*, projecting laterally on each side of the web, so as to engage on one side the upper edge of the washer and on the other side the upper edge of the nut *l*. The thickness of web *i* corresponds to the difference between the thickness of the main portion of the washer and portion *h*. The web *i* has in its lower edge a notch, *m*, which registers with the bolt-hole in the washer. The flange *k* is extended beyond the web *i*, as at *n*, and said extended end is made thinner than the rest of the flange, so that it may be bent down over the corner of the washer, as shown in dotted lines in Fig. 1. The opposite end of the key is made solid

the full thickness of the width of flange *k*, and thus forms a suitable head to receive the blows of a hammer for driving the key in. Said head also forms a shoulder, *o*, which fits against the side of the nut. A lug, *p*, projects from the upper side of the key to receive the blows of a hammer for driving the key out.

The operation of my device is as follows: The washers *D D* are slipped upon the projecting ends of the joint-bolts *c c*. The nuts are then screwed upon said bolts close against the washers. Key *E* is then inserted, from the side toward which the nut has been turned on, between the back of the nut and the thin portion of the washer, rib *j* entering groove *f*, and the key is driven until shoulder *o* comes in contact with the side of the nut. As the key passes over that portion of the threads of the bolt which is in its path, the bolt is forced slightly downward and the threads are battered down. The slight recoil of the bolt and threads causes the bolt to engage the notch *m*, and thus prevents the withdrawal of the key until some considerable force is applied against the lug *p*. For still greater security, the extension *n* of flange *k* may be bent down over the washer, as before described. It will be observed that, the key having been inserted from the side toward which the nut was turned when screwed on, any tendency of the nut to turn in the opposite direction operates to draw the key in rather than to push it out along the path in which it is forced to move, if it moves at all, by the interlocking of rib *j* and groove *f*.

I claim as my invention—

The above described nut-lock, consisting of the grooved rectangular washer having the thin portion *h*, the key *E*, having the central web, *i*, notch *m*, rib *j*, flange *k*, and lug *p*, all combined and arranged to co-operate with a bolt and nut, as and for the purpose specified.

WILLIAM H. THOMPSON.
